UNITED STATES PATENT OFFICE

ANDERS PETER ANDERSEN, OF COPENHAGEN, DENMARK

CRUSHER HEAD FOR HOMOGENIZING APPARATUS

Application filed July 2, 1929, Serial No. 375,489, and in Denmark May 26, 1928.

The present invention relates to an arrangement in crusher heads for homogenizing apparatus of the kind by which the crushing surfaces on the upper as well as on the lower members are fitted with grooves or the like, serving to produce eddies in the liquid passing through, in order to increase the intensity of the mixing, and the invention consists in offsetting the grooves in the two members 5 relatively to each other for the purpose of preventing the accumulation of stationary liquid in the grooves.

One individual embodiment is illustrated on the drawing, which shows a vertical longitudinal section of a crusher head.

The crusher head consists of a bottom member 1 and a top member 2. The bottom member 1 is fitted with a central supply channel 3 and ends at top in a crusher surface 4 which as shown may suitably be shaped as a spherical segment fitted along the edge with a plane shoulder 5. The top member 2 is similarly fitted with a crusher surface 6 shaped like a concave spherical segment corresponding to the convex crusher surface 4 and with a plane shoulder 7. The shoulders 5 and 7, besides being an extension of the crusher surface, serve also as guides for the two parts of the crusher head. Above the orifice of the supply channel 3 the top member is fitted with a circular recess 8, and the crusher surfaces of both members are fitted with grooves 9 or similar suitable arrangements which are offset relatively to each other.

When the liquid is forced out between the crusher surfaces the grooves of the same will produce eddies in the liquid flowing past and, thereby, further the homogenization essentially.

As mentioned before the crusher surfaces in the embodiment shown are partly spherical, as this shape in the present case is most suitable, but there is of course nothing to prevent the crusher surfaces from having other suitable forms.

Having now described my invention, what I claim as new and desire to secure by Letters Patent is:

A crusher head for homogenizing apparatus including top and bottom members hav-

ing circular concentric grooves in the adjacent surfaces thereof, the grooves in one member being concentric with the grooves in the other member and the grooves in the respective members being relatively offset whereby during operation of the members particles of material are given an eddy movement in each groove and are crushed in other positions during their following movement toward the next following groove of the members.

In testimony whereof I affix my signature.

ANDERS P. ANDERSEN.
